UNITED STATES PATENT OFFICE.

CHARLES S. BUSHNELL, OF ROCHESTER, NEW YORK, ASSIGNOR TO GENERAL RAILWAY SIGNAL COMPANY, OF GATES, NEW YORK, A CORPORATION OF NEW YORK.

TRACK ELEMENT FOR TRAIN-CONTROL SYSTEMS.

Application filed November 6, 1922. Serial No. 599,339.

To all whom it may concern:

Be it known that I, CHARLES S. BUSHNELL, a citizen of the United States of America, residing at Rochester, in the county of Monroe and State of New York, have invented certain new and useful Improvements in Track Elements for Train- Control Systems, of which the following is a specification.

10 This invention relates to trackway devices for inductively transmitting control influences to moving trains, and particularly to means for supporting such devices.

In train control systems of the intermittent type, it has been found desirable to transmit control influences from the trackway to a moving vehicle through an intervening air gap, and without physical contact between the devices on the vehicle and 15 along the trackway. One method of transmitting such influences is by magnetic communication between such devices, either directly by magnetic action, or by the induction of an electric current due to the rate 20 of change of magnetic flux communicated from one device to the other. In devices of this kind, it is important that the relation between the trackway and car-carried device, especially the air gap between such 25 devices, be maintained the same, or nearly so, in order that proper control influences may be transmitted. If such trackway devices are supported by the usual ties of the 30 track, it is sometimes found that the rails 35 cut or work their way into the ties, thereby bringing the ties and the track devices up with respect to the rails, while at other times the rails may be shimmed up by putting tie- 40 plates between the rails and ties, thereby lowering the track devices with respect to the rails, and increasing the air-gap correspondingly. If the track device is mounted 45 in this manner and on the outside of the rails, it is also possible, due to unequal cutting of the rails into the ties, to bring the trackway device down with respect to the plane defined by the top of the rail.

With the above and other considerations in mind, the principal objects and purposes 50 of the present invention contemplate the provision of a strong and durable supporting structure for supporting trackway devices of this kind directly from the track rails, and in a manner that does not inter-

fere with the proper operation of the train 55 or of the signaling system.

Other objects will be in part pointed out and in part obvious from the following detail description of several embodiments of 60 this invention.

In describing the invention in detail, reference will be made to the accompanying drawings, in which:

Figure 1 shows a plan view of a preferred form of the invention in connection with a 65 short section of trackway;

Fig. 2 is a side elevation of the trackway devices shown in Fig. 1, having parts broken away for clearness;

Fig. 3 is a sectional view taken on the line 70 3—3 of Fig. 1, as viewed when looking in the direction of the arrows;

Fig. 4 is a plan view similar to Fig. 1 of a modified form of the invention; and

Fig. 5 is a section taken on the line 5—5 75 of Fig. 4, as viewed in the direction of the arrows.

Referring particularly to Figs. 1, 2 and 3 which show the preferred method of supporting an inductive or magnetic influence 80 transmitting device directly from the rails of the trackway, the rails 1 and 2 are supported on ties 3 in the usual manner. It is assumed that these rails 1—2 form portions of the usual closed circuit trackway 85 system of a railway block signal system. Supported from these rails 1—2 are cross beams 4 which in the present instance comprise inverted track rails, presumably comprising rails which have been worn so badly 90 as not to be useful as a running rail. These beams 4 are supported underneath the rails by clamped plates 5 bolted to these beams 4 by bolts 6. The rail 2 is insulated from the beams 4 by a strip of insulation 7 extending around the foot of the rail to space the rail from both the beams 4 and the clamped plates 5.

The beams 4 in the particular embodiment of the invention shown extend to one side 100 of the trackway a suitable distance to support an influence transmitting track element. On these extending ends of the beams 4 is bolted a block of insulation 8 by bolts 9, this insulation being preferably of 105 a weather and fireproof character, which at the same time is tough and does not readily disintegrate under severe vibrations, such as

fiber board, asbestos board, and the like. To the insulating blocks 8 is bolted by bolts 10 an inverted channel 11, preferably made of non-magnetic material, having its ends bent downward to form a sloped ramp portion. These sloped portions may also extend adjacent the ties 3 in a manner to prevent end-wise movement and displacement of the channel member 11. Near the middle of this channel member 11 is provided an elongated opening to accommodate the track element proper.

A hood or shell 12, having sloping ends 13 and provided with depressed portions 14, is bolted to the channel member 11 by bolts 15, having their heads disposed in the depressed portions 14. This hood 12 is constructed of suitable non-magnetic material, such as manganese steel or the like, and is provided with two shallow square pockets or depressions to accommodate pole pieces. Between these pockets is a slot which is filled with a block of wood 12^a or other insulating material, so as to avoid eddy currents. These pockets have an opening in the bottom, and have the pole pieces 16 fastened by screws 18 to the flange 17 formed around said opening.

To the pole pieces 16, which are made of a high grade of magnetic material, is screw fastened a yoke 19 by screws 20 having their heads countersunk into these pole pieces. This yoke 19 may comprise a core of laminated magnetic material, or a U-shaped bar forming a permanent magnet, depending on the particular system with which the trackway device is to be used, the legs of this yoke being provided with coils 21, only one of which has been shown. These coils may be used to magnetize the yoke for influence transmitting purposes when the yoke is constructed of unmagnetized magnetic material, may be used for opposing the flux due to a yoke comprising a permanent magnet, or may be used by being short-circuited at times to prevent a sudden change of flux through this yoke, depending on the particular train control system with which it is to be used.

In Fig. 4 has been illustrated a modified form of the present invention in which the beams 4¹ do not extend entirely to the remote rail 2, but are bolted to a bar of iron 22 by bolts 23, this bar 22 being fastened to ties by lag screws 24. The remaining elements of this modified form of the invention being the same have been given the same reference characters. It should be noted that this construction provides a substantial support similar to that shown in Figs. 1, 2 and 3, but does not require additional insulation between the cross beams 4¹ and the rail 2, such insulation being facilitated by the ties 3 themselves.

It should be noted that the embodiment

of the preferred form of the invention shown provides a supporting structure for inductive influence transmitting devices which maintains a predetermined alignment and relation between the track rails and such device, regardless of the relation between the ties and the rails. If, due to a passing train, the rails move with respect to the ties and the ballast, the trackway device will move similarly and therefore maintain the same relation between this inductive trackway device and the moving vehicle, so that if the vehicle is provided with an inductive receiving element the relation between this element and the inductive trackway device will be the same regardless of movement of the rails with respect to their foundation.

In the modified form of the invention, as shown in Figs. 4 and 5, substantially the same results are accomplished although some slight movement of the influence transmitting device with respect to the track rails is possible, because the remote ends of the beam 4¹ are connected directly to the ties, and therefore if the ties move with respect to the rails a corresponding movement will be transmitted to the inductive trackway device. It should, however, be noted that the bar 22 is fastened to the ties 3 a considerable distance from the rail 1, so that the lever arm comprising that portion of the beam 4¹ is considerably longer than the lever arm comprising the beam 4¹ extending between rail 1 and the inductive trackway device, so that the relative movement between the ties 3 and the rails 1 will have very little effect upon the movement of this trackway device with respect to a plane formed by the top of the rails.

Having thus shown and described several specific embodiments of the invention, I desire to have it understood that the specific structure shown and described is merely illustrative, and does not exhaust the various embodiments thereof, and that various additions and modifications may be made without departing from the scope of this invention.

What I claim is:—

1. A device of the character described comprising, a pair of track rails, ties for supporting said track rails, means extending underneath said track rails and fastened thereto, and an electro-magnetic device including a core of magnetic material supported by said last mentioned means.

2. A device of the character described comprising, a pair of track rails, ties for supporting said track rails, means extending underneath said track rails and fastened thereto but insulated from one of them, and an electro-magnetic device including a core of magnetic material supported by said last mentioned means.

3. A device of the character described comprising, a pair of track rails, ties for supporting said track rails, means fastened to said rails having an extension extending 5 from one side thereof, an electro-magnetic influence transmitting device supported on said extension, and means for insulating said last mentioned means from one of said rails.
- 10 4. A device of the character described comprising, a pair of track rails, ties for supporting said track rails, means fastened to said rails having an extension extending from one side thereof, and an electro-magnetic 15 influence transmitting device supported on said extension, said electro-magnetic device comprising a yoke having a coil thereon, a housing of non-magnetic material 20 for said device, and means for supporting said housing directly by both rails of a railway track.
5. A device of the character described comprising, a pair of track rails, ties for supporting said track rails, means fastened to said rails and extending to one side a considerable distance beyond the outside face of 25 one of said rails, and an electro-magnetic influence transmitting device supported on said means, said electro-magnetic device
- comprising a support of non-magnetic material, and a yoke carried by said support having coils surrounding said yoke.
6. A device of the character described 30 comprising, an electro-magnetic influence transmitting device adapted to transmit control influences to a moving railway vehicle including a U-shaped core having a coil thereon, a housing of non-magnetic material 35 for said device, and means for supporting said housing directly by both rails of a railway track.
7. Means for transmitting control influences from the trackway to a moving vehicle 40 comprising, a non-magnetic shell having depressed portions to form pockets, pole pieces in said pockets, a core supported by said pole pieces having coils thereon, and means for supporting said shell from two track 45 rails in a manner to insulate said rails from each other and to insulate said shell from both of said rails.

In testimony whereof I hereby affix my signature.

CHARLES S. BUSHNELL.
